ATTACHMENT FOR COPY HOLDING LINE
INDICATING MACHINES

George S. Smith, Chicago, Ill.

Application May 27, 1935, Serial No. 23,726

4 Claims. (Cl. 120—29)

My present invention relates to the provision of an attachment for copy holding, line indicating machines. Copy holding machines are devices for holding the manuscript or other "copy" in convenient position for the typist to follow while making a typewritten transcript thereof. Such machines, having a panel with means for detachably securing copy to the top of the panel provided with a line guide with means for feeding the panel with the copy attached vertically with respect to the line guide as the lines are read, are now upon the market. Such machines as are now obtainable are made in a number of sizes to take copy of different breadths, and if copy is wider or broader than the machine is designed for, a larger size of machine must be employed.

My object has been to provide an attachment for such a machine which will permit the use of the machine with much wider copy than it was designed to accommodate.

Another object of my invention is to provide an attachment which will permit the lowering or raising of the registry of the line guide. That is, by means of my attachment the relation of the line guide to the copy may be either elevated above or depressed below the position where the line guide provided with the machine rested upon the copy. Such an adjustment will often be found convenient and desirable.

I have attained the foregoing objects by means of the structure illustrated in the accompanying drawing, in which—

Fig. 1 is a front elevation of the attachment.

Fig. 2 is a top plan thereof.

Fig. 3 is a vertical section, on line 3—3 of Fig. 1, showing the arrangement of clip by means of which the attachment is secured to the line guide of a copy holding machine.

Fig. 4 is a schematic elevation of the class of machine with which my attachment is designed to be associated.

Similar reference characters refer to similar parts throughout the respective views.

A typical copy holding, line guiding or indicating machine with which my invention is designed to cooperate consists of a base 5 supporting for vertical movement a panel 6, upon the top of which panel is provided means 7 for detachably holding "copy". A line guide or indicator 8 is associated with the machine in such a way that by operating a lever 9 the panel with the copy attached is elevated and adjusted, predetermined distance to indicate the line which is next to be copied. The means by which the

panel is moved and the distance that it is moved is no portion of the present invention.

My attachment consists of a blank 10 of sheet metal, or other suitable material, one edge 11 whereof is bent to lie opposite to and parallel with the body of the blank. The curved or bent portion between the turned up edge 11 and the body of the blank 10 is cut away intermediate the ends of the blank to provide the slot 12. A strengthening or stiffening bead 13 is preferably provided in the bent up edge 11. Upon the back 10 of the blank 10 is secured, by rivets or in any other desired way, the U-shaped spring clips 14. In my experience two of such spring clips, suitably spaced from each other, have been all the attaching means that are either requisite or desirable.

By placing the attachment so that the original line guide 8 of the machine extends between the body of the blank and the adjacent portion of the U-clip 14 the top of the bent-up edge 11 20 of the attachment functions as the line guide and is positioned generally somewhat lower than the top of the original line guide 8. If, on the other hand, the line guide is inserted under the outermost layer of the U-shaped spring clip, the bottom edge of the bent over portion 11 25 functions as the line guide and is generally disposed above the edge of the original line guide 8. It will, of course, be understood that when my attachment is in position and use the copy extends through the slot 12 and not behind the original line guide 8.

It will be seen from the foregoing description, taken in connection with the drawing, that by means of this simple and inexpensive attachment that the smallest copy holding and line guiding machine may be adapted to operate with greater width of copy than the apparatus was designed to or capable of operating before, which 40 relieves the possessor of such an attachment of the necessity of buying machines of different sizes and of accommodating such machines when purchased.

Having described my invention what I claim 45 is new and desire to secure by Letters Patent is:

1. An attachment for copy holding, line indicating apparatus comprising a blank formed to provide spaced, parallelly disposed strips with a slot or channel extending between said strips 50 to points adjacent their ends and means for attaching the rear of said strips to the line indicating element of a copy holding, line indicating machine.

2. An attachment for copy holding, line in- 55

dicating apparatus comprising a blank formed to provide spaced, parallelly disposed strips of metal with a slot or channel extending between said strips to points adjacent their ends, and 5 spring clips extending from the rear of said strips to the line indicating element of a copy holding, line indicating machine.

3. An attachment for copy holding, line indicating apparatus comprising a blank formed to provide spaced, parallelly disposed strips of 10 metal with a slot or channel extending between said strips to points adjacent their ends, and

U-shaped spring clips extending from the rear of said strips to the line indicating element of a copy holding, line indicating machine.

4. A line indicating attachment for copy holding, line indicating machines consisting of a front beaded strip and a back strip secured in spaced relation at their ends and means carried by said back or rear strip for securing the same to a line indicating element of a copy holding and line indicating machine with either edge 10 of said strips which may be desired uppermost.

GEORGE S. SMITH.
